SHUTTLE

Emil E. Fuller, Woonsocket, R. I., assignor to
 Shambow Shuttle Company, Woonsocket,
 R. I., a corporation of Rhode Island

Application April 28, 1931. Serial No. 533,381

2 Claims. (Cl. 139—212)

The present invention relates to an improvement in shuttles and more particularly to shuttles receiving the skewerless or internal wound cop wherein the yarn is drawn from the center 5 of the thread mass.

The object of the invention is to improve this type of shuttle and the invention consists in the improvement hereinafter described and particularly defined in the claims.

10 In the accompanying drawing, Fig. 1 is a plan view of the shuttle embodying the present invention; Fig. 2 is a vertical axial section taken on the line 2—2 of Fig. 1; Fig. 3 is a similar section, enlarged, of a portion of the 15 left-hand end of Fig. 2; Fig. 4 is a section taken on the line 4—4 of Fig. 3; and Fig. 5 is a section taken on the line 5—5 of Fig. 3.

The shuttle body 10 is provided with the usual cop cavity 11 to receive the internal wind cop 20 12. The side and bottom walls of the cop cavity are provided with the usual serrations 13 for holding the cop in place in the cavity. A cavity cover 14 is provided, hinged at one end 25 at 15 on the body of the shuttle. It extends the length of the cop cavity and holds the cop in place in the cavity. The opposite end of the cop cavity cover is held in closed position by a catch indicated in a general way by the reference character 16. The catch consists of a pivoted double bail 17 which engages two hooks 18 30 projecting from the end of the cop cavity cover. A coil spring 19 normally tends to turn the bail 17 clockwise on its pivot pin into the position shown in Figs. 2 and 3. The under side of the 35 free end of the cavity cover is provided under the catches with two cams 20, each adapted to engage one of the two portions of the bail 17 and when the cavity cover is pressed downward to close the cover on the cop, the cams 20 engage 40 the two portions of the bail respectively and turn the bail to the left, i. e. counter-clockwise, as viewed in Fig. 3, so that the hooks 18 are depressed with the result that the bail portion 17 45 may snap over the hooks and engage the hook projections 18. Between the two bail portions is a thread opening 21 (Fig. 4) through which the yarn passes on its way to the shuttle eye 22. The cop cavity cover 14 is pressed downward 50 on the cop and held down by the bail catch 16. Near the catch is provided a support 23 for the free end of the cavity cover which engages the lateral edges of the cover only and in the illustrated embodiment, it is connected 55 by the portion 24 which is below the level of the ends of the support 23, and leaves a yarn space 25 through which the yarn drawn from the cop passes above the connection 24 (see Fig. 5). The support 23 is a round pin sup- 60 ported in aligned holes in the opposite sides of

the shuttle body, with the middle of the pin cut away to form the yarn space, as shown.

Heretofore this cavity cover support has been a continuous support extending transversely of the shuttle supporting cover, but the cover has 65 pressed the yarn against the support in such case and created a heavy drag upon the yarn. This support has also caused a gathering of lint shed by the yarn as it passes between the cover and the support. The shuttle is also provided 70 with a thread tension device 26 between the opposed faces of which the yarn is drawn and this supplies a tension to the yarn. In threading the shuttle, the cop is first placed in position, as shown in Fig. 2, and the free end of the yarn 75 is drawn between the jaws of the tension device 26, the cover is closed, and the yarn is then pulled down into the thread passage 27 by which it is led to the delivery eye 22.

A feature of the invention is the elimination 80 of the cover support tension by providing the shuttle with the edge supports for the cavity cover.

The cop cavity cover is opened by applying pressure with the thumb or fingers of the hand upon the free end of the cover and then sliding the thumb or fingers against the catch bail 17, thereby pushing it beyond the hooks 18, thereby permitting the free end of the cover to spring up so that it may be lifted by the hand to afford access to the cop cavity for the insertion of a cop.

What is claimed is:

1. A shuttle having, in combination, a shuttle body provided with the usual cop cavity to receive an internal wind cop, a cop cavity cover to close the top of the cavity fastened at one end of the cavity to the body, a pivoted catch at the other end of the cavity to engage the free end of the cover and a cam on the cover to engage and open the catch on movement of the cover into closed position.

2. A shuttle having, in combination, a shuttle body provided with the usual cop cavity to receive an internal wind cop, an imperforate cop cavity cover to close the top of the cavity hinged at one end of the cavity, a cover catch at the opposite end of the cavity, a support for the cover near the catch engaging the side edges of the cover only and having a central recess forming a thread guide space between the cover and the support, said body having a delivery eye and a tension for the yarn between the cop cavity and the eye.
